United States Patent Office.

MERRITT L. THOMPSON, OF FLEMINGTON, NEW JERSEY, ASSIGNOR TO HIMSELF AND JOHN P. RITTENHOUSE, OF THE SAME PLACE.

Letters Patent No. 70,050, dated October 22, 1867.

IMPROVED BARREL-HEAD.

The Schedule referred to in these Letters Patent and making part of the same.

TO ALL WHOM IT MAY CONCERN:

Be it known that I, MERRITT L. THOMPSON, of Flemington, in the county of Hunterdon, and State of New Jersey, have invented and made a certain new and useful Improvement in Heads for Barrels, &c.; and I do hereby declare the following to be a full, clear, and exact description of the said invention, reference being had to the annexed drawing making part of this specification, wherein—

Figure 1 is a plan of said barrel-head.

Figure 2 is a section of the same at the line *z z*.

Figure 3 is a section at the line *y y*, and

Figure 4 is a section separately of the blocking-piece in a slightly modified form.

Similar marks of reference denote the same parts.

Heretofore it has been necessary to loosen the end hoops of the barrel or keg in order to take the head out; this injures the hoops and also the ends of the staves, and the barrel can seldom be used a second time and be as secure as when first headed up.

The nature of my said invention consists in a peculiarly-constructed head, that can be removed or replaced without loosening the hoops, thereby preventing injury to the barrel and allowing of its being used several times. This improvement is particularly adapted to the heads of flour-barrels, butter-casks, paint-kegs, &c.

In the drawing *a* represents the barrel-staves, hooped together in any usual manner, *b* the groove around the inside, near the end, for the reception of the head. *c c* are the side segments of the head, fitted with ribs on their inner edges, shown by dotted lines in figs. 1 and 3, upon which ribs the edges of the middle sections *d d* of the head rest. These sections *d d* do not touch each other, but leave a hole through the head at or near the middle of the barrel, into which is inserted the blocking-piece *e*. The periphery of the head, when the parts are set together, corresponds to the size of the groove *b*. The side segments *c c* of the head are first put into the barrel, then the sections *d d* are put in, and afterwards the blocking-piece *e*, which fills the hole in such a manner that the sections cannot be separated until said blocking-piece is removed, after which said head can be removed in the reverse order in which the sections are put in. The blocking-piece *e* has side flanges 1 1 to prevent its falling into the barrel, and end flanges 2 2 to prevent its falling out, said flanges 2 2 taking under the edges of the sections *c c*. In order to remove this blocking-piece there is enough end play allowed to admit of the said blocking-piece being driven endwise to clear one of the flanges 2, so that it may be lifted out. To prevent this end motion to the block from any accidental cause, I employ a peg, 3, driven in, as seen in figs 1 and 3, or else I carry the upper part of said block along in the form of a flange, 4, and insert a small nail to hold the said blocking-piece in place.

This barrel will be much stronger in the chime than the usual flour-barrel, because it does not require the ends of the staves to be so much bevelled as has heretofore been done for facilitating the introduction of the head. In place of a rib and groove to form the joint between the edges of the sections, the same may be made bevelled inwardly on the side sections, the centre sections being correspondingly bevelled, and wider on their outside than on their inside surfaces.

What I claim, and desire to secure by Letters Patent, is—

The blocking-piece *e*, formed as set forth, in combination with the sections *c c* and *d d* composing the head, as and for the purposes specified.

In witness whereof I have hereunto set my signature this twenty-seventh day of July, 1867.

M. L. THOMPSON.
